SHEAR

Joseph M. O'Malley and Fred B. Fay, Worcester, Mass., assignors to Morgan Construction Company, Worcester, Mass., a corporation of Massachusetts

Application May 22, 1943, Serial No. 488,974

10 Claims. (CL. 164—42)

This invention relates to shears, and more particularly to flying shears capable of severing the rapidly traveling hot metal product of a rolling mill.

It is one object of the invention to provide a flying shear of comparatively simple and inexpensive construction and thoroughly dependable in operation.

It is a further object of the invention to provide a flying shear capable of cutting metal bars while they are traveling at relatively high speeds.

It is a further object of the invention to provide a flying shear suitable for cutting rolled metal bars as they travel from the finishing stand of a merchant mill to the cooling bed.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts.

Fig. 1 is a plan view of a flying shear, with certain parts broken away for clearness of illustration;

Fig. 2 is a side elevation of the shear, likewise with certain parts broken away;

Fig. 3 is a section on the line 3—3 of Fig. 1;

Fig. 4 is a section on the line 4—4 of Fig. 1;

Fig. 5 is a fragmentary elevation taken on the line 5—5 of Fig. 1; and

Fig. 6 is an electrical wiring diagram.

The embodiment illustrated comprises a frame 10 in which are journaled two parallel horizontal shafts 11 mounted one above the other so that the metal bars to be severed may travel between them. On each shaft there is mounted an arm 12 provided with a blade 14, these arms normally converging rearwardly toward the on-coming bars at an angle of approximately ninety degrees. These bars approach the shear from a merchant rolling mill or the like along a horizontal guideway 15 and are directed between the blades 14 by means of a forwardly converging trough 16. The rear end of this trough is connected to the guideway 15 by a vertical pivot pin 18, and its front end rests on the frame 10. After leaving the shear the bars travel along a horizontal guideway 19 which may lead to a cooling bed (not shown).

Power actuated means is provided to swing the arms 12 simultaneously in a forward direction and thereby sever the bars. For this purpose the shafts 11 are extended outwardly beyond the

frame 10, and on the outer end of each shaft there is mounted an arm 21 which extends in substantially the same direction as the corresponding blade-supporting arm 12. These arms are connected by links 22 to the opposite ends of an upright bar 23 which is carried by the slidable piston rod 25 of a fluid motor 26. This motor comprises a horizontal cylinder 27 mounted on the frame 10 at one side of the guideway 19 and parallel therewith. Within the cylinder there is provided a slidable piston 28 which is secured to the front end of the piston rod 25. This rod is shown with a rearward extension 30 which is slidably supported in a guide 31 mounted on the side of the frame 10. Near the rear end of the cylinder 27 there is provided an inlet port 33 to which a suitable pressure fluid, such as compressed air, is supplied through a pipe 34. Near the front end of the cylinder there is provided an exhaust port 35 which is controlled by a slidable exhaust valve 37 having a stem 38 extending forwardly therefrom. On the front end of the cylinder 27 there is mounted a bracket 39 which supports a solenoid 41 having a vertically reciprocable plunger 42. This plunger is connected to the front portion of the valve stem 38 by means of a bell crank lever 43. The bracket 39 has a lug 45 thereon to support a screw 46 located directly in front of the valve stem 38. This screw forms an adjustable stop to limit the forward movement of the valve stem and thus control the amount the valve 37 can open. A restricted by-pass is provided for the piston 28, and as shown in Fig. 2 this by-pass may be in the form of a small port 48 through the piston itself. These various parts are so constructed and arranged that upon energization of the solenoid 41, the plunger 42 will be drawn upwardly, sliding the valve 37 forwardly and opening the exhaust port 35. The air will immediately exhaust from the front end of the cylinder 27, allowing the compressed air in the rear end of the cylinder to force the piston forwardly, thus swinging the blades 14 forwardly into engagement with the stock to sever the same. Since the effective length of the blade-supporting arms 12 is about twice that of the driving arms 21, the blades 14 will travel at approximately twice the speed of the piston. Shortly after the blades have passed the mid-point of their travel and severed the stock, the piston will close the exhaust port 35, thus trapping air in the front end of the cylinder to form a cushion and aid in decelerating the piston. Upon de-energization of the solenoid 41, the weight of the released plunger 42 will slide the exhaust valve 37 rearwardly and

close the port 37. Air from the pipe 34 will flow through the by-pass port 48 into the front end of the cylinder, and as the pressure becomes equalized on the opposite sides of the piston the latter will move rearwardly for the reason that the effective area of its rear face is less than that of its front face by the amount of cross sectional area afforded by the piston rod 25.

In order that the return movement of the blades 14 may take place without interference with the stock, the stock is moved laterally to one side of the blades. For this purpose the trough 16 is swung laterally by means of a fluid motor 50 into the position indicated by the broken lines in Fig. 1. This motor comprises a horizontal cylinder 51 mounted on the rear portion of the frame 10 with its axis transverse to the line of stock travel. Within the cylinder there is provided a slideable piston 52 from which a piston rod 54 extends inwardly, this rod being connected by a link 55 to the trough 16. The movements of the piston 52 are controlled by a slideable four-way valve 57 from which ports 58 and 59 lead to the inner and outer ends of the cylinder respectively, this valve being supplied with a suitable pressure fluid, such as compressed air, through a pipe 61. A stem 62 extends outwardly from the valve 57, and the outer end of this stem is connected by a bell-crank lever 63 (Fig. 5) to the vertically reciprocable plunger 65 of a solenoid 66. This solenoid is supported by a bracket 67 mounted on the outer end of the cylinder 51. These parts are so constructed and arranged that upon energization of the solenoid 66 the plunger 65 will be pulled upwardly, sliding the valve 57 inwardly. This will admit compressed air from the pipe 61 through the port 58 to the inner end of the cylinder 51, while at the same time opening the outer end of the cylinder to the atmosphere through the port 59. The piston 52 will thereupon move outwardly, swinging the trough 16 and moving the stock out of the path of the blades 14. Upon de-energization of the solenoid 66, the weight of the plunger 65 will cause it to descend, sliding the valve 57 outwardly to the position shown in Fig. 1. This will admit compressed air to the outer end of the cylinder and exhaust air from the inner end, so that the piston will move inwardly and return the trough 16 to its original position.

It is important that the trough 16 should move the stock out of the path of the blades 14 very soon after the cut has been completed, and that the stock should not be returned until the blades have swung back sufficiently to avoid interference therewith. In order that the apparatus may operate in this manner automatically, means is provided to energize the solenoid 66 substantially at the time the blades reach the vertical plane defined by the axes of the shafts 11, on their cutting stroke, and to maintain this energization until the blades reach the same position on their return stroke. For this purpose a switch 68 is mounted beneath the lower arm 21 in a position to be closed at the proper time by a sector 70 which projects from the hub portion of this lower arm. As shown in Fig. 6, the switch 68 is connected in series with the solenoid 66 across a suitable source 71 of electricity. The solenoid 41 is connected in series with a push button switch 72 across the source 71.

The operation of the invention will now be apparent from the above disclosure. With the solenoids 41 and 66 both de-energized the parts will occupy the positions shown in the drawings. 75

The piston 29 will be at the rear end of the cylinder 27, and the blades 14 will be at the rear-most points in their arcs of travel. The piston 52 will be at the inner end of the cylinder 51, and the trough 16 will be positioned to guide the stock directly between the blades 14. When a cut is to be made, the operator will simply close the push button 72 momentarily. This will energize the solenoid 41, lifting the plunger 42, 10 and pulling the valve stem 38 forwardly against the stop 46. The air in the front end of the cylinder will thereupon escape through the port 35, and the compressed air in the rear end of the cylinder will immediately expand and force the piston 29 forwardly. This will swing the arms 12 and the blades 14 forwardly to sever the stock. By proper adjustment of the screw 48, which determines the amount of opening of the exhaust valve 37, the operator can regulate the 15 speed of the piston 29 and thus cause the speed of the blades at the time of the cut to be substantially equal to the speed of the stock. Because of the simple and direct connection between the piston and the blades, the moving parts have a comparatively low inertia, and it is possible to obtain very rapid acceleration. Furthermore, the speed of the blades is approximately twice that of the piston. For these reasons the shear is adapted for severing very 20 rapidly traveling bars. At substantially the time the cut is completed, the sector 70 will close the switch 69 and thus energize the solenoid 66. This will raise the plunger 65, slide the valve 57 inwardly, and cause the motor 50 to swing the trough 16 outwardly, thereby moving the stock laterally away from the path of the shear blades. By the time the main piston 29 reaches the exhaust port 35 and begins to decelerate from the compression of the air trapped in the 25 front end of the cylinder, the solenoid 41 will be de-energized and the weight of the plunger 42 will have closed the exhaust valve 37. The air pressures on the two sides of the piston will soon equalize through the port 48, and the piston will move rearwardly because of the larger effective 30 area of its front face. As the blades 14 pass the midpoint of their travel on the return stroke, the sector 70 will allow the switch 69 to open, de-energizing the solenoid 66. The plunger 65 35 will thereupon descend, pulling the valve 57 outwardly and causing the motor 50 to swing the trough 16 inwardly to its original position, so that the stock will again travel between the blades 14 in readiness for the next cut.

55 The apparatus is comparatively simple and inexpensive to manufacture, thoroughly dependable in operation, and well adapted for use in conjunction with a merchant rolling mill.

Having thus described our invention, what we 60 claim as new and desire to secure by Letters Patent is:

1. A flying shear for severing stock as it travels longitudinally in a generally horizontal direction comprising two parallel horizontal shafts located 65 respectively above and below the line of stock travel, two blade-carrying arms on the respective shafts normally converging rearwardly toward the on-coming stock, a blade on each arm, an actuating arm on each shaft extending substantially parallel with the corresponding blade-carrying arm, a fluid-pressure actuated motor having a slideable piston rod substantially parallel with the line of stock travel, links connecting the piston rod with the actuating arms to swing them forwardly and then rearwardly, and

guide means to direct the stock between the blades during their forward movement and at one side of the blades during their rearward movement.

2. A flying shear for severing stock as it travels longitudinally in a generally horizontal direction comprising two parallel horizontal shafts located respectively above and below the line of stock travel, two blade-carrying arms on the respective shafts normally converging rearwardly toward the on-coming stock, a blade on each arm, an actuating arm on each shaft extending substantially parallel with the corresponding blade-carrying arm, a fluid-pressure actuated motor spaced forwardly from the actuating arms, the motor having a piston rod which extends rearwardly substantially parallel with the line of stock travel, links connecting the piston rod with the actuating arms to swing them forwardly and then rearwardly, and guide means to direct the stock between the blades during their forward movement and at one side of the blades during their rearward movement.

3. A flying shear for severing stock as it travels longitudinally in a generally horizontal direction comprising two parallel horizontal shafts located respectively above and below the line of stock travel, two blade-carrying arms on the respective shafts normally converging rearwardly toward the on-coming stock, a blade on each arm, an actuating arm on each shaft extending substantially parallel with the corresponding blade-carrying arm, the effective length of the actuating arms being considerably less than the effective length of the blade-carrying arms, a fluid-pressure actuated motor spaced forwardly from the actuating arms, the motor having a piston rod which extends rearwardly substantially parallel with the line of stock travel, links connecting the piston rod with the actuating arms to swing them forwardly and then rearwardly, and guide means to direct the stock between the blades during their forward movement and at one side of the blades during their rearward movement.

4. A flying shear for severing stock as it travels longitudinally in a generally horizontal direction comprising two parallel horizontal shafts located respectively above and below the line of stock travel, two blade-carrying arms on the respective shafts normally converging rearwardly toward the on-coming stock, a blade on each arm, an actuating arm on each shaft extending substantially parallel with the corresponding blade-carrying arm, a cylinder spaced forwardly from the actuating arms, a piston slidable in the cylinder, a port for the admission of pressure fluid to the rear end of the cylinder, a port for the exhaust of fluid from the front end of the cylinder, a valve to control the exhaust port, a restricted by-pass port for the piston, a piston rod extending rearwardly from the piston, links connecting the piston rod with the actuating arms to swing them forwardly when the exhaust valve is opened and then rearwardly when the exhaust valve is closed, and guide means to direct the stock between the blades during their forward movement and at one side of the blades during their rearward movement.

5. A flying shear for severing stock as it travels longitudinally in a generally horizontal direction comprising two parallel horizontal shafts located respectively above and below the line of stock travel, two blade-carrying arms on the respective shafts normally converging rearwardly toward the on-coming stock, a blade on each arm, an actuating arm on each shaft extending substan-

tially parallel with the corresponding blade-carrying arm, a fluid-pressure actuated motor spaced forwardly from the actuating arms, the motor having a piston rod which extends rearwardly substantially parallel with the line of stock travel, links connecting the piston rod with the actuating arms to swing them forwardly and then rearwardly, laterally swinging guide means for the stock approaching the blades, a motor connected to the guide means to swing the same, a pilot device for the last-mentioned motor, and actuating means for the pilot device arranged to cause the guide means to move the stock laterally out of the path of the blades when they have swung forwardly past their cutting position and then to move the stock laterally back into the path of the blades after they have swung rearwardly once more.

6. A flying shear for severing stock as it travels longitudinally in a generally horizontal direction comprising two parallel horizontal shafts located respectively above and below the line of stock travel, two blade-carrying arms on the respective shafts normally converging rearwardly toward the on-coming stock, a blade on each arm, an actuating arm on each shaft extending substantially parallel with the corresponding blade-carrying arm, a fluid-pressure actuated motor spaced forwardly from the actuating arms, the motor having a piston rod which extends rearwardly substantially parallel with the line of stock travel, links connecting the piston rod with the actuating arms to swing them forwardly and then rearwardly, laterally swinging guide means for the stock approaching the blades, a fluid-pressure actuated motor connected to the guide means to swing the same, a pilot valve for the last-mentioned motor, a solenoid to actuate the pilot valve, a switch to control the solenoid, and actuating means for the switch arranged to cause the guide means to move the stock laterally out of the path of the blades when they have swung forwardly past their cutting position and then to move the stock laterally back into the path of the blades after they have swung rearwardly once more.

7. A flying shear for severing longitudinally traveling stock comprising a pair of cooperating blades pivotally supported about parallel axes on opposite sides of the stock, the axes extending transversely of the stock, means to swing the blades forwardly through arcuate paths to sever the stock and then rearwardly through the same paths to their original positions, and guide means to direct the stock between the blades during their forward movement and at one side of the blades during their rearward movement.

8. A flying shear for severing longitudinally traveling stock comprising a pair of cooperating blades pivotally supported about parallel axes on opposite sides of the stock, the axes extending transversely of the stock and the blades being normally stationary in positions located rearwardly of the plane defined by the axes, means to swing the blades forwardly through arcuate paths to sever the stock and then rearwardly through the same paths to their original stationary positions, and guide means to direct the stock between the blades during their forward movement and at one side of the blades during their rearward movement.

9. A flying shear for severing longitudinally traveling stock comprising two parallel shafts on opposite sides of the stock, and extending transversely thereof, a blade carried by each shaft, means to turn the shafts in one direction to

swing the blades forwardly through arcuate paths to sever the stock and then in the reverse direction to swing the blades rearwardly through the same paths to their original positions, and guide means to direct the stock between the blades during their forward movement and at one side of the blades during their rearward movement.

10. A flying shear for severing longitudinally traveling comprising two parallel shafts on opposite sides of the stock and extending transversely thereof, two blade-carrying arms on the respective shafts normally extending rearwardly

from the plane defined by the shaft axes, a blade on each arm, means to turn the shafts in one direction to swing the blades forwardly through arcuate paths to sever the stock and then in the reverse direction to swing the blades rearwardly through the same paths to their original positions, and guide means to direct the stock between the blades during their forward movement and at one side of the blades during their rearward movement.
